UNITED STATES PATENT OFFICE

2,030,388

AIR OR GAS EXTRACTOR FOR VEHICLES
OR BUILDINGSJames Muirhead and David Prain Muirhead,
Glasgow, ScotlandApplication October 28, 1933, Serial No. 695,676
In Great Britain November 16, 1932

8 Claims. (Cl. 98—20)

This invention has reference to apparatus for extracting air, smoke or other gases from buildings, vehicles or other stationary or movable structures, including the compartments of road or rail vehicles, the cabins or other compartments of ships or aircraft, domestic or industrial ventilating flues, smoke stacks and outlet or uptake flues and including the bonnets or cowlings and scuttles of automobile and aircraft engines. The improved extractor can be utilized for example upon the outlet ends of gas fire flues or upon the outlet ends of flues built into the walls of buildings, or it can be used for ventilating a cavity wall, or to extract fumes from uptake flues leading from enclosed compartments, such as kinematograph operators' cabins or other enclosed spaces from which air, steam, smoke or other gases are to be removed.

A further object of the invention is to provide for the efficient drainage of rain water or melted snow from the extractor, so that any liability of flood water entering through the extractor into the building or other structure will be wholly or almost entirely eliminated.

It is a further object of the invention to enable the flue upon which the extractor is mounted to be cleaned without removal of the extractor from the flue.

The extractor may be mounted upon or be unitary with an upstanding tubular shaft or hollow trunk which may be of oblong, square, circular, oval or other cross-section.

The extractor is provided with a movable section in its upper part so that, by moving the movable upper section, access can be had to the interior of the extractor and the tubular shaft or trunk, so that a brush or the like can be passed through the extractor when cleaning the uptake or flue upon which it is mounted.

The invention will be hereinafter described with reference to the accompanying drawing whereon the same reference characters are used as those employed in our prior patent specification No. 1,728,001 to designate corresponding parts.

On the drawing Fig. 1 shows an extractor according to the present invention applied to the coping of a cavity wall which forms an uptake flue.

Fig. 2 is a vertical section through the extractor of Fig. 1.

Fig. 3 is a perspective view of a half section of a further form of extractor according to the invention.

Figs. 1 and 2 show a hollow double wall 23 with

an intervening cavity 24 which is blocked as and where required to form a vertical uptake flue 26 in the manner well known in building construction. Surmounting one of these uptake flues we have shown one form of our extractor which comprises a base plate 6 having an aperture therein surrounded by an upstanding tubular shaft or hollow trunk 7. The trunk 7 may be formed by two parallel plates as shown or it may be of oblong, square, circular or other cross-section. A cowl is disposed over the trunk 7, the cowl having a pair of depending parallel baffles 8 which preferably extend to a point at or just below the level of the upper edge of the trunk 7. The top of the cowl is shown in the form of a sliding cover 11, being provided with inturned edges which engage beaded edges on parts 11c of the cowl. The parts 11c are preferably curved to form rain gutters or melted snow channels. The sliding cover 11 has a handle 25 to enable it to be drawn in either direction, so that a brush can be passed through the flue 26 and trunk 7. The ends of the cowl are closed by end plates 13 which extend down to the base plate 6. At opposite sides of the cowl are air channels 20 formed by outer sloping deflectors 18, the ends of the two deflectors being connected together by the end plates 13. As clearly seen in Fig. 2, the base plate 6 is turned over at 6a over the outer edges of the double wall and the sloping deflectors 18 are spaced a short distance from the double wall and extended at 18b down to about the lower edge of the turned-over part 6a of the base plate 6, so that an opening 19 is left along each side of the base of the extractor. The openings 19 are relatively narrow and serve to discharge water or melted snow which may collect in the channels 20 and the openings 19 are shielded by the lower edges or extensions 18b of the sloping deflectors 18, so as to prevent wind currents from entering the extractor through the openings 19. The base plate 6 may slope towards the openings 19. The down-turned edges 6a serve to bind the extractor to the brick-work of the wall.

The extractor may be built in between coping stones 28 and the latter may be shaped to conform to the external shape of the extractor as shown, being provided with rain channels 29. It will be understood that in such case the joints between the coping stones and the extractor will be cemented or made water-tight in any well-known manner.

It will also be apparent that one or more of the extractors shown in Fig. 1 could be fitted to the

top of cavity parapet walls for ventilating the same.

The air, smoke or other gas rising in the trunk 7 passes over the top thereof into the channels 20, from which it is extracted by the suction of wind currents passing over the upper edges 18a of the deflectors 18.

Fig. 3 illustrates an extractor of the form shown in Figs. 1 and 2 having a cylindrical trunk 7 which can be fitted inside or around an uptake flue, such as an uptake flue leading from a gas fire or from a living room or workroom. In this case the base plate 6 is shown sloping towards the openings 19, and it will be manifest that the base plate 6 in Fig. 2 may slope downwards towards the openings 19.

We claim:

1. In a ventilator, a hollow shaft communicating with the space to be ventilated, a four sided outer structure comprising two end walls and two transverse upwardly and inwardly inclined deflector plates spaced from said shaft, a cowl above said shaft comprising baffles extending from end wall to end wall between said shaft and said deflectors, said baffles and deflectors forming two elongated slots terminating at the top in substantially parallel openings at opposite sides of said shaft, and base means extending outward from said shaft at a distance below said baffles, 30 but terminating just short of said deflectors to provide drainage slots between the base means and said deflectors.

2. A ventilator as described in claim 1, wherein the bottom edges of said baffles terminate approximately at the level of the top of said shaft.

3. A ventilator as described in claim 1, wherein said cowl projects above the level of said openings.

4. A ventilator as described in claim 1, wherein said hollow shaft extends from end wall to end wall and said base means comprises two plates extending from opposite sides of said shaft.

5. A ventilator as set forth in claim 1 wherein said deflectors extend below the level of the base means to provide protecting lips for the drainage slots.

6. A ventilator as set forth in claim 1 wherein said base means comprises two plates extending from opposite sides of said shaft and each provided at its outer edge with a downwardly projecting flange, and said deflectors extending below the level of said base means to provide protecting lips for the drainage slots formed between said flanges and the protecting lips.

7. A ventilator as set forth in claim 1 wherein said cowl includes a movable closure at the top thereof whereby access may be had to the interior of the ventilator.

8. A ventilator as claimed in claim 1 wherein said base means slopes downwardly towards the drainage slots.

JAMES MUIRHEAD.
DAVID PRAIN MUIRHEAD.
